UNITED STATES PATENT OFFICE.

WILLIAM K. BENEDICT, OF NEW YORK, N. Y., ASSIGNOR TO THE CO-OPERATIVE BUILDING PLAN ASSOCIATION, OF SAME PLACE.

DESIGN FOR THE EXTERIOR OF A HOUSE.

SPECIFICATION forming part of Design No. 20,085, dated August 12, 1890.

Application filed July 15, 1890. Serial No. 358,849. Term of patent 7 years.

To all whom it may concern:

Be it known that I, WILLIAM K. BENEDICT, of the city and county of New York, in the State of New York, have invented and produced a new and original Design for the Exterior of a House, of which the following is a specification, reference being had to the accompanying drawings.

Figure 1 represents a perspective view of a house showing my design. Fig. 2 represents a longitudinal section or plan of the first story. Fig. 3 represents a horizontal section or plan of the second story.

Similar letters of reference designate corresponding parts in all the figures.

A house of this design consists of a first story and a second and third attic stories contained in a hip roof, from which dormer-windows project, and has a wing or L extension projecting from the rear thereof, a piazza around the front and one side thereof, a similar piazza contained in one corner of the ex-

tension, and a tower springing up from one corner of the roof and surmounted by an ogee roof, all as hereinafter more particularly described with reference to the drawings.

A B C designate the exterior of the first story and second and third attic stories contained in the hip roof D, from which dormer-windows d, having gable or hip roofs e, project, and at one corner of which is a tower E, surmounted by an ogee roof e. A piazza F extends along the front and one side of the house, and is covered by the main roof D. At the rear of the house is a wing or L extension G, surmounted by a hip roof g, in one corner of which is a smaller piazza h.

What I claim as my design is—

The design for the exterior of a house, substantially as herein shown and described.

WILLIAM K. BENEDICT.
